HENRY C. STANLEY, OF NEW YORK, N. Y.

CLOSURE FOR GARMENTS.

No. 829,287.

Specification of Letters Patent.

Patented Aug. 21, 1906.

Application filed April 29, 1904. Serial No. 204,529.

To all whom it may concern:

Be it known that I, HENRY C. STANLEY, a citizen of the United States, and a resident of the city of New York, borough of Manhattan, in the county and State of New York, have invented a new and Improved Closure for Garments, of which the following is a full, clear, and exact description.

The object of this invention is to provide a novel closing device for women's garments, such as the closure for a shirt-waist, body of a dress, or the placket of a dress-skirt, which will be simple, neat in appearance, and convenient in use, and will dispense with the employment of buttons or the like for the purpose indicated.

The invention consists in the novel construction and combination of parts, as is hereinafter described and defined in the appended claims.

Reference is to be had to the accompanying drawings, forming a part of this specification, in which similar characters of reference indicate corresponding parts in all the figures.

Figure 1 is an exterior view, in part, of a dress-waist at its closure, showing the improved flap-closing devices applied thereto and partially closing or securing them in contact at their vertical edges. Fig. 2 is an inner side view of the waist portion shown in Fig. 1, showing the flaps and the improvement applied thereto, the closing operation being partially completed. Fig. 3 is an enlarged perspective inner side view of a dress or shirt waist at and near the upper edge thereof, showing the improvement applied thereto and the waist-flaps closed by its connection therewith. Fig. 4 is a partly sectional perspective view of the exterior of a waist in part, the section being taken substantially on the line 4-4 in Fig. 1, showing the closing device applied and holding together the edge portions of the waist. Fig. 5 is a sectional perspective view substantially on the line 5-5 in Fig. 1, showing a shirt-waist in part and the closing device thereon. Fig. 6 is an enlarged fragmentary view showing a part of Fig. 2. Fig. 6^a is a vertical transverse sectional view taken substantially on the line 6^a-6^a in Fig. 6, seen in direction of the arrows in said figure. Fig. 7 is a longitudinally-shortened side view of a closing-strip which is a detail of the invention, and Fig. 8 is an interior detached

side and upper end view of a keeper-loop, which in suitable number is employed.

In the drawings, 10 indicates the rear portion of a dress-body or shirt-waist, the flaps of which are to be detachably held connected and their side edges slightly lapped by means of the improvement. Two spaced and resilient thin busk-strips 11 12 are employed, which are of equal length and width and have parallel side edges, and on these busk-strips a series of similar keeper-loops 13 are mounted 65 and preferably evenly spaced apart. As best shown in Fig. 8, each keeper-loop consists of the rear flat section e, the narrow side sections a a, at right angles thereto, and the front flange-sections e² e², forming continuous unbroken sections of the busk-strips and extending parallel with the rear section e. One of these loops is always located at the extreme upper end of my device, and the upper adjacent corners e' e' of the busk-strips 75 are rounded or beveled to form a flaring mouth, as it were, at the upper end of the upper loop.

In the busk-strip 11 a pair of spaced perforations b' are formed close to each other at 80 the rear of each of the loops, (see Fig. 8,) and in the part of said busk-strip between the loops other pairs of perforations b are formed, (see Figs. 4, 5, and 8,) which perforations afford means for securing the busk-strip 11 85 upon an appropriate flap 10^b of the dress-body or shirt-waist 10, as indicated by stitches f, which pass through the pairs of perforations b b' and through the fabric of the shirt-waist.

Along the side edge of the flap 10^b a casing 10^a is formed or secured, which is of such width as to be adapted to loosely fill the interior space in each keeper-loop 13 when inserted therein. This casing may be made of 95 any soft flexible material.

To join together the side edges of the waist-flaps, a closing-strip 14 is employed. This consists of a flap-strip of resilient sheet metal or other available material of a proper length 100 to extend through the casing 10^a and project somewhat therefrom at each end of the casing, it being understood that the latter is of an equal length with that of the body or shirt-waist opening. The closing-strip 14 is 105 widened somewhat, as at d, at and near the upper end thereof, affording a head to enable the free manipulation of the strip and pre-

vent it from passing down too far in the casing 10^a, and, as shown in Fig. 7, the lower end 5 of the closing-strip is tapered edgewise, so as to facilitate the insertion of said strip into the casing.

The space between the busk-strips 11 and 12 is such as will permit the free lateral passage of the casing through said space or opening into the keeper-loops, the rounding of the 10 upper corners *e'* of the busk-strips facilitating such an insertion.

When the dress-body or shirt-waist having the improvement is to be closed at the edges of its flaps after the garment is donned, the 15 closure of the flaps is effected by first inserting the upper end of the casing 10^a into the gap between the ends of the busk-strips at the upper keeper-loop. The operator having in hand the closing-strip 14 now inserts the 20 lower end *e* thereof into the casing 10^a at its upper end and passes the strip downward thereinto. This will spread the casing laterally into the said upper loop, and as the strip is passed downward the casing will in the 25 same manner be entered successively in the series of keeper-loops 13, which will cause a distension of the casing in said keeper-loops, locking it therein and obviously closing the side edges of the waist-flaps in contact with 30 each other.

Upon the neckband 10^c of the body or shirt-waist 10 a hook *g* and mating eye *g'* are secured near the ends of said band, which hook and eye may be engaged with each 35 other after the closing-strip 14 has been inserted into the casing 10^a, and the latter is thus drawn into the keeper-loops 13.

At the waist-line of the body or shirt-waist 10 a hook *h* may be placed on one flap and an 40 eye *h'* on the other flap of the garment, these when engaged serving to finish the closure of the flaps, and the ends of the busk-strips, closing-strip, and casing may all be concealed by a waist ribbon or belt usually worn with 45 a dress or shirt waist.

To release the fastening of the flaps for a removal of the garment, the hooks and eyes *g g'* and *h h'* are first disengaged and then the closing-strip 14 is withdrawn from the 50 casing 10^a by an upward pull, which will permit the pliable casing to pass out of the openings in the keeper-loops 13, which will release the side edges of the garment.

It will be evident that the improved closure for garments may be readily applied to the placket of a skirt, the operation for closing and opening the placket being similar to that already described for the closure and release of the flaps of a dress-body or shirt-waist.

While the busk-strips and loops of my device are shown and described as integrally formed, it is obvious that they may be formed separately and then connected together by

securing the flanges of the loops to the busk-strips.

Having thus described my invention, I claim as new and desire to secure by Letters Patent—

1. A closure for a garment comprising two busk-strips, a plurality of keeper-loops on the busk-strips, all open at the same side, a closing-strip, and a casing on a garment-body or waist, said closing-strip being insertible through the keeper-loops for engaging and holding said casing on the garment-body. 70

2. A closure for a garment comprising two busk-strips spaced apart and secured on the same flap edge of a garment-body or waist, a plurality of spaced keeper-loops, secured to 80 said busk-strips, a resilient closing-strip, insertible through all the keeper-loops, and a casing on an edge of one flap adapted to be engaged by said closing-strip and drawn into the keeper-loops thereby in sequence. 85

3. A closure for a garment comprising two resilient busk-strips spaced apart and having parallel side edges, a plurality of keeper-loops secured on said busk-strips so as to project at the same side thereon at intervals, and 90 a flat closing-strip that is resilient and insertible endwise through all the keeper-loops in sequence, one busk-strip being secured upon a side edge of a flap on a garment-body or waist, the other side edge of the garment, 95 having a casing thereon adapted to be drawn into the keeper-loops and held therein by an insertion of the closing-strip through the loops and casing.

4. A garment-closure comprising two busk-strips adapted to be secured at one side of an opening in a garment, a plurality of keeper-loops secured to said busk-strips and holding the same spaced apart, and a closing-strip insertible in the keeper-loops and adapted to 105 engage a flexible casing at the other side of the garment-opening to draw the casing into said loops in sequence, through the space between the busk-strips, and to hold said casing in said loops. 110

5. A garment-closure, comprising a plurality of open and spaced loops united by connecting means, said loops and connecting means being adapted to be secured to a garment at one side of an opening therein, and a 115 closing-strip adapted to be received into said loops and carry with it through the openings in the loops, a portion of the garment at the other side of the garment-opening.

6. In a garment-closure, the combination 120 with a garment having an opening, of a casing-like member having its front and rear sides approximately parallel and provided in one side with a longitudinal opening, said casing-like member being of a length approximately equal to the length of the garment-opening and secured to one side of said opening, and a closing member of greater 125

width than the opening in the casing-like member and adapted to be received into the casing-like member and carry with it through the opening therein a portion of the garment at the other side of the garment-opening.

- 5 7. A garment-closure, comprising a pair of strips spaced apart and connected with each other by a plurality of spaced loops projecting from one face of said strips, the strips being adapted to be secured to a garment at one side of an opening therein, and a flat closing-
10 strip of a width greater than the space be-

tween the loop-carrying strips and adapted to be received into the said loops and carry with it through the space between the strips 15 a portion of the garment at the other side of the garment-opening.

In testimony whereof I have signed my name to this specification in the presence of two subscribing witnesses.
